Inventor:
William M. Guslin
by Clyde L. Rogers
his Atty.

UNITED STATES PATENT OFFICE.

WILLIAM M. GUSTIN, OF HINGHAM, MASSACHUSETTS, ASSIGNOR OF ONE-HALF TO
ELDEN H. JENNISON, OF WESTON, MASSACHUSETTS.

CLOTH-FOLDING APPARATUS.

1,354,294.

Specification of Letters Patent. Patented Sept. 28, 1920.

Application filed April 6, 1920. Serial No. 371,673.

To all whom it may concern:

Be it known that I, WILLIAM M. GUSTIN, a citizen of the United States, and resident of Hingham, county of Plymouth, Commonwealth of Massachusetts, have invented an Improvement in Cloth-Folding Apparatus, of which the following description, in connection with the accompanying drawings, is a specification, like characters on the drawings representing like parts in each of the several views.

This invention relates to apparatus for laying a web of cloth or other sheet material in a series of superposed folds upon a table or like support so that the several layers of cloth may be died or blanked out to the required form simultaneously. Apparatus for this purpose adapted to draw the cloth web from a supply roll and lay the same upon the table has hitherto been devised, but so far as I am aware previous apparatus of this type has been relatively slow in operation being adapted to lay only one fold at a time and requiring the manipulation of rods or bars upon the movable table and the fixed support between the laying of successive folds. The principal object of the present invention is to provide means comprising a car or carrier movable over the table on which the cloth is to be laid and equipped with means for drawing out from a relatively stationary support, a series of folds simultaneously and of such a number as may be required for dieing out simultaneously, requiring thus only a single operative movement of the car to lay a substantial number of folded layers superposed one upon another. The foregoing and other objects and advantages of the invention will more fully appear from the following detailed description, and the distinctive features of novelty will be thereafter pointed out in the appended claims.

Referring to the drawings:

Figure 1 is a side elevation of an apparatus embodying the invention;

Fig. 2 is a plan view thereof;

Fig. 3 is a front end view of the car, the track being shown in section on line 3—3 of Fig. 2;

Fig. 4 is an end view of the stationary frame from which the cloth is drawn and showing the rolls mounted in such frame over which the cloth passes;

Fig. 5 is an enlarged partial vertical section on line 5—5 of Fig. 2; and

Fig. 6 is a fragmentary section on line 6—6 of Fig. 2.

10 indicates a table upon which the folded layers of the cloth are to be laid. In practice this table will be of a width determined by the widest width of the cloth web that is to be handled and of a length corresponding to the length of the folded layers to be laid, *e. g.*, often fifty feet or more, the particular length being determined by conditions of use, since the invention is not in any wise limited in this respect. At one end of this table is mounted a stationary frame 11 having a mounting 11^a for a roll of cloth 10 R from which the web W to be folded is drawn. This frame has side portions 11^b, 11^c spaced apart a somewhat greater distance than the width of the cloth web. One of these side portions has swingingly mounted at the front thereof a frame 12 from which extend a series of round bars or rods 13 constituting axles on which are rotatably fitted rolls 14. The frame 10 is shown as equipped with a series of tongues 12^a through which is passed a pivot rod 15 fitted vertically through the front end of the frame portion 11^c and constituting the pivot on which the frame 12 swings. The axle rods 13 are of a length to extend across to the other side frame portion 11^b and their extremities 13^a which are shown as squared are adapted to engage in seats 16 provided therefor in the front of the frame portion 11^b. The frame portion 11^b has slidably fitted therein a vertical bar 17 equipped with a series of lateral projections 18 with down-turned extremities 18^a which constitute catches adapted to hold the rod ends 13^a in their respective seats 16 when they are moved thereinto. The bar 17 is normally held downward so that these catches hold the axle rods in place, by a coil spring 19 and the bar is equipped with a projecting head 20 constituting a handle by which it may be lifted to disengage these catches when the rolls are to be swung outward as presently explained. The outer sides of the catches 18^a are preferably beveled as indicated at 18^b so that the rod ends on being pressed into their seats may lift the bar 17 and permit the rod ends to be seated without requiring the separate manual lifting of the

bar 17. This mounting of the rolls 13 thus permits them to be swung outward from the side frame portion 11^c so that they would extend alongside the end portion of the 5 table, and since the side portion 11^c is spaced laterally outward from the table, these rolls would then occupy a position so that the car will be clear of them in its movement over the table as now to be explained. 10 10 indicates a car mounted on a track 22, the rails of which extend at the respective sides of the table 10. This car is shown as driven by an electric motor 23 connected through reducing gearing 24 to an axle 25 thereof, 15 though this manner of driving the car is merely illustrative. This car has mounted at the front thereof a frame work equipped with spaced apart horizontal forward projections 26 at each side thereof. These projections 26 at one side of the car have pivoted thereto as indicated at 27 axle rods 28 bearing rolls 29, these pivots being on the same side of the mechanism as the side portion 11^c of the stationary frame. The projections 26 at the other side of the car are equipped with seats 30 adapted to receive the outer extremities of the rods 28 when these are swung thereinto, these extremities being shown as squared as indicated at 31. 30 Spring pressed catches 32 are provided for holding these rod extremities in their respective seats when they are moved thereinto, these catches having projecting heads 32^a to serve as hand pieces and having outwardly beveled sides 32^b to permit the rod extremities to press them back and snap past them as they are inserted into their seats. 35 In use the car is run up toward the frame 11 until the spaced apart projections 26 extend through and between the bearings at the ends of the rolls 13 and positioning the rolls 29 on the car inward past the plane of the rolls 13. Then the end of the cloth web W is drawn over a suitable guide roll 33 and dropped down vertically between the rolls 13 and the rolls 29 and the end thereof secured in a suitable clip 34 at the bottom of the frame 11. Then on moving the car outward along the track 22 the rolls 29 will engage 40 the cloth and draw it between the respective rolls 13 to produce a series of folds F which with the employment of the number of rolls shown will be eight in number, i.e., one more than the total number of rolls. At this point 45 it should be understood that while I show herein three rolls mounted on the stationary frame co-operative with four rolls on the car, that these numbers are merely illustrative and that more or less rolls may be employed according to the number of folds which it 50 may be desired, or practicable to produce simultaneously in any particular material. As the car is moved outward over the track 22 the folds will thus be laid upon the table 55 evenly superposed and of a length deter-

mined by the length of the table and of the car movement. If desired the roll R from which the cloth is drawn may be motor actuated so as to facilitate the feeding off of the cloth, this feature involving no particular requirements as to structure being not however shown herein. When the full lengths of the folds have been laid the rolls 29 are released from the catches 32 and swung outward so as to remove them from 75 the folds and likewise the rolls 13 are released by the catch bar 17 and swung outward so as to disengage them from the folds so that the cloth may then lay perfectly flat upon the table and the car may be returned 80 for another operation. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the 85 invention. 90

Having described my invention, what I claim as new and desire to secure by Letters Patent is:

1. Cloth folding apparatus, comprising a relatively stationary frame equipped with a series of horizontal rolls spaced apart vertically and mounted for swinging movement from one end thereof, a table to receive the cloth folds, and a car mounted to operate on a track over said table, said car bearing a series of horizontal rolls vertically spaced apart and mounted so as to pass between the rolls on said frame to a position inward thereof, said car rolls having a mounting to swing from one end thereof. 100 105

2. Folding apparatus, comprising a relatively stationary frame bearing a set of horizontal rolls vertically spaced apart, and a car mounted for movement toward and from said frame and bearing a set of horizontal vertically spaced apart rolls arranged to enter between the rolls of said frame to a position inward thereof, the rolls on said car and said frame having a mounting permitting them to swing from one end thereof to disengage them from the material folds after the folds are laid. 110 115

3. Folding apparatus, comprising a relatively stationary frame having a mounting for a cloth roll, a set of horizontal vertically spaced apart rolls mounted in said frame to swing from one end thereof, the frame having an equipment for detachably locking the other ends of said rolls thereto, and a car mounted for movement toward and from said frame, and bearing a set of horizontal vertically spaced apart rolls arranged and adapted to enter between the rolls on said frame to a point inward thereof, said car rolls having a mounting permitting move- 120 125 130

ment thereof to disengage them from the cloth folds.

4. Cloth folding apparatus, comprising a stationary frame bearing a series of horizontal vertically spaced apart rolls, a car mounted for movement toward and from said frame having a series of horizontal vertically spaced projections from the front thereof adapted to enter between the axles

of said frame rolls, and a series of rolls 10 pivoted at one end to the projections on said car, said projections equipped with means for detachably locking the other ends of said rolls thereto for the purpose stated.

In testimony whereof I have signed my 15 name to this specification.

WILLIAM M. GUSTIN.
